UNITED STATES PATENT OFFICE.

FREDERICK C. NOYES, OF ALEXIS, ILLINOIS.

MARKING-TAG.

1,110,509.

Specification of Letters Patent.

Patented Sept. 15, 1914.

Application filed November 10, 1913. Serial No. 800,202.

To all whom it may concern:

Be it known that I, FREDERICK C. NOYES, a citizen of the United States, residing at Alexis, in the county of Warren and State 5 of Illinois, have invented certain new and useful Improvements in Marking-Tags, of which the following is a specification, reference being had to the accompanying drawings.

10 This invention relates to new and useful improvements in marking tags and has for its object to provide a device of this character which, when applied, is not adapted to mar the fingers of those having use for the 15 articles upon which the tags are applied.

A further object of the invention resides in providing a tag of improved structure which is simple and durable in construction, inexpensive to manufacture and one which 20 will be very efficient and useful in operation.

With these and other objects in view, the invention consists in the novel features of construction, combination and arrangement of parts as will be hereinafter referred to 25 and more particularly pointed out in the specification and claims.

In the accompanying drawing forming a part of this application, Figure 1 is a plan view of the strip used in the construction of 30 my improved device. Fig. 2 is a vertical section therethrough. Fig. 3 is a plan view of the U-shaped wire member. Fig. 4 is a similar view of the strip of flexible material applied to the strip shown in Fig. 1. Fig. 5 is a plan view with the parts of the device applied one to the other prior to the folding 35 and securing of the same together. Fig. 6 is a vertical section therethrough. Fig. 7 is a section through the device showing the same applied to use. Fig. 8 is a similar view 40 showing the device prior to the bending of the same to the position shown in Fig. 7. Fig. 9 is a plan view of the device prior to the bending thereof; and Fig. 10 is a similar 45 view showing the same bent and engaged properly with a piece of material.

In describing my invention, I shall refer to the drawing in which similar reference characters designate corresponding parts 50 throughout the several views and in which—

1 indicates a strip of card-board or heavy paper lined on one side with a strip of fabric 2 of less width than the strip 1, to strengthen the same. This strip 1 is bent 55 upon itself intermediate of its ends and a U-

shaped wire member 3 is disposed between the bent sections of the strip, the arms thereof being projected through openings in the looped or bent edge thereof. The extreme free ends of these arms of the wire 60 loop 3 are slightly bent and sharpened to provide prongs 4. The wire or U-shaped member 3 is so disposed between the sections of the strip 1 as to permit the prongs or the like to rest against the looped or bent portion of the same and project from one face 65 thereof.

Disposed between the bent sections of the strip 1, is a block 5 formed preferably of heavy paste-board, said block being of a 70 width substantially equal to the width of the strip of fabric and of a length less than the length of the strip as doubled upon itself. This block 5 is adapted to be positioned between the bent sections of the strip 75 1 so as to dispose one edge of the same slightly above the free ends of the doubled sections of said strip, and said doubled sections of the strip together with the block 5 therebetween are adapted to be secured one 80 to the other by the application of an adhesive to the faces thereof. In order to secure the U-shaped or looped wire member 3 in position between the portions of the device, one face of the block 5 is provided with 85 a substantial U-shaped groove 6 which receives the base portion of the member 3 therein and when the sections of the strip 1 are secured together by the adhesive against the faces of the block 5, it will be seen that 90 said member 3 will be securely held in position.

In the application of the tag to use, the same is adapted to be bent transversely thereacross in the plane of the inner edge of 95 the block 5, it being understood that the piece of material to which the tag is to be attached, is disposed against the face of the tag toward which the prongs 4 are directed. Thus when the portion of the tag at which the prongs 4 are disposed, is bent over upon the other portion thereof, said prongs will be forced through the piece of material and into the portion of the tag having the block 5 therein. The strip 1 is formed with a 100 pair of grooves 7, the grooves serving to weaken the strip where the points 4 are adapted to engage the same, so that the points may be readily passed through the strip 1 and enter the fabric strip 2, so as to 105 110

permit the tag to be securely held to the material when bent in engagement therewith.

From the foregoing description of the construction of my improved device, the manner of applying the same to use will be readily understood and it will be seen that I have provided an improved tag which will positively prevent the fingers of the operator from being injured in the application to and the removal of the tag from use. It will also be seen that the device is one which is simple and durable in construction, inexpensive to manufacture and one which will be very efficient and useful in operation.

While I have particularly described the elements best adapted to perform the functions set forth, it is obvious that various changes in form, proportion and in the minor details of construction may be resorted to without departing from the spirit or sacrificing any of the principles of the invention.

Having thus described this invention, what I claim is:—

1. A marking tag of the class described comprising a strip doubled upon itself and having the sections thereof secured together to form a body, a stiffening member secured between the sections of the body at one end of the same, and prongs projecting from the other end of said body adapted to be received in said stiffening member upon the doubling of the body upon itself.

2. A marking tag of the class described comprising a strip doubled upon itself and having the sections thereof secured together to form a body, a block of flexible material secured between the sections of the body at one end of the same to form a stiffening member therein, and a U-shaped wire member also secured between the sections of said body and having the arms thereof projected slightly from the end thereof opposite that at which the stiffening member is disposed,

said last mentioned projecting portions being designed to form laterally extending prongs.

3. A marking tag of the class described comprising a strip doubled upon itself and having the sections thereof secured together to form a body member, a flexible block secured between the sections of said body member at the free ends thereof, one face of said block being provided with a U-shaped groove, and a U-shaped wire member secured between the sections of said body, the base portion of said wire member being received in the groove of said block and the outer ends of the arms thereof being projected slightly beyond the opposite end of the body and designed to form laterally extending prongs.

4. A marking tag of the class described comprising a strip doubled upon itself and having the sections thereof secured together to form a body, a block of flexible material secured between the sections of the body at one end thereof to form a stiffening member therein, said stiffening member being disposed at the end of the body formed by the free end portions of the sections of the strip, whereby to space one end of said block from the looped portion of said strip, and a U-shaped wire member secured between one face of said block and one section of the doubled strip having the arms thereof projected through the loop in the doubled strip, the free ends of said arms being bent laterally to form prongs and one section of the doubled strip and the adjacent face of the block being scored to receive the prongs therein when the strip forming the body is bent upon itself.

In testimony whereof I hereunto affix my signature in the presence of two witnesses.

FREDERICK C. NOYES.
